PACKAGING APPARATUS AND METHOD

Mervin Allatt, Plainfield, N. J., assignor to Millie Patent Holding Co., Inc., a corporation of New York

Application July 2, 1938, Serial No. 217,210

13 Claims. (Cl. 93—2)

This invention relates to an improved packaging method and a wrapping apparatus thereof. The embodiment of the invention herein described and shown is directed to the packaging of small flat-shaped articles in sealed wrappers, such as individually wrapped tea-balls of the like.

Among the objects of the invention is to generally improve packaging methods and apparatus of the character described including wrapping machines, which shall comprise few and simple parts assembled to operate continuously for packaging flat-shaped articles like tea-balls, in quantity production, which shall be capable of operating either as independent units, or in connection with automatic article manufacturing apparatus, such as tea-ball making machines as attachments for receiving and individually wrapping in continuous operation the complete outputs of such tea-ball making machines, which shall be reliable in performance of its operation without requiring a minimum of attention in supervision and labor, which shall be relatively inexpensive to manufacture, and which method and apparatus shall be economical and efficient to a high degree in use.

Other objects of the invention will in part be obvious and in part hereinafter pointed out. The invention accordingly consists of features of construction and method, combinations of elements, arrangements of parts and steps in the process of manufacture which will be exemplified in the construction and method hereinafter described and of which the scope of the application will be indicated in the following claims.

In the accompanying drawings in which is shown various possible illustrative embodiments of this invention.

Fig. 1 is a front elevational view of the machine constructed to embody the invention for packaging tea-balls individually in wrappers of paper, "Cellophane" or the like sheet material;

Fig. 2 is a rear elevational view of the machine shown in Fig. 1;

Fig. 3 is a detailed plan view corresponding to a section as seen from lines 3—3 of the machine shown in Fig. 1;

Fig. 4 is an end elevational view corresponding to a section as seen from lines 4—4 in Fig. 2;

Fig. 5 is a cross-sectional view taken on lines 5—5 in Fig. 3;

Figs. 6 and 7 are cross-sectional views taken on lines 6—6 and 7—7 respectively, in Fig. 5;

Fig. 8 is a detailed cross-sectional view corre-

sponding to a section as seen from lines 8—8 in Fig. 3;

Fig. 8a is a fragmentary detailed view of the bag transfer showing the members in position for sealing the package after receiving the same from the position shown in Fig. 8;

Fig. 9 is a fragmentary detailed view of the feed conveyor and the transfer mechanism, the latter being shown in position to receive the tea bag wrapper during the portion of the wrapping operation prior to that shown in Fig. 8;

Figs. 10, 11 and 12 are cross-sectional views taken on lines 10—10, 11—11 and 12—12 respectively, in Fig. 9;

Fig. 13 is a fragmentary view of the feed conveyor and the transfer mechanism similar to Fig. 9 showing the transfer mechanism reeded after receiving a wrapper;

Fig. 14 is a cross-sectional view taken on lines 14—14 in Fig. 13;

Fig. 15 is a fragmentary plan view of the feed conveyor showing the gate serving as a barrier to the advancing passage of a tea-ball during the period of wrapping and sealing operations of a prior tea-ball;

Fig. 16 is a fragmentary view showing tea-ball aligning means for causing a wiping movement in the folding operation of the wrapper;

Fig. 16a is a detail section of the tea-ball aligning means.

Figs. 17 and 18 are front and side elevational views, respectively, showing the package of an individually wrapped tea-ball produced by the improved machine; and

Fig. 19 is an enlarged cross-sectional view taken on lines 19—19 in Fig. 17.

This invention provides an improved method and apparatus for packaging any flat-shaped articles in sealed wrappers. The embodiment herein described and shown in the drawings is directed to the packaging of tea-balls using apparatus constructed for operation as an independent unit where the tea-ball or other similar articles are fed by hand or otherwise from a supply source, or may be attached to a suitable discharge conveyor of an automatically operated tea-ball making machine such as shown in Patent No. 2,068,724 to Wiczulski and Pizzolanteta granted January 26, 1937, and my co-pending patent application Ser. No. 37,257, filed August 21, 1935, so that the manufacture of finished tea-balls and individual wrapping thereof may be carried out in a continuous operation to provide sanitary packages.

Referring now to the drawings, in Fig. 17 a

package 30 manufactured in accordance with the embodiments of the invention herein described, is shown, said package 30 comprising of a seam sewn tea-ball 31 sealed in a wrapper 32. The wrapper may be made of any suitable sheet material preferably of paper, as for example, that commercially known as "diaphane" paper, or of "Cellophane," said sheet material preferably having the property of being capable of forming a tight joint when the superimposed edge portions of the wrapper 32 are pressed together while heated without the use of adhesives to form the wrapper sealed joint 31a as clearly shown in Figs. 17, 18 and 19. Said seam joint 31a may be corrugated as at 31b to serve as a border trimming band extending around the wrapper as seen from Figs. 17 and 19.

The complete apparatus which is designated generally at 40 is assembled on a bed frame or base 41 which supports the various moving parts on suitable upright members 42. These upright members form a rigid frame structure with the base 41 and support a horizontally extending belt conveyor C at a desirable height or level above the base 41. Said conveyor C may correspond to and serve as the discharge conveyor of an automatically operated tea-ball machine such as shown in the drawings and described in the aforesaid patent, or in that of my said co-pending patent application, said patent and application each including means for discharging the finished tea-balls on a horizontally extending discharge conveyor. Such discharge means to the conveyors of tea-balls in tea bag making machines being broadly old and well known in the art, such means are not shown or further described herein. It is to be understood, however, that where it is found desirable, the conveyor C of the apparatus 40 may be installed to serve as a discharge conveyor or equivalent thereof of a tea-ball making machine and the apparatus 40 would then be used as an attachment whereby complete tea-balls would be automatically delivered to the apparatus 40 by means of the conveyor C and then automatically fed for individual wrapping by said apparatus 40 in the manner hereinafter described in one complete continuous operation. The apparatus 40 may also be used as an independent unit by placing the completely finished tea-balls or other flat articles on the conveyor C manually or by any suitable mechanical feeding means in the well understood manner. The conveyor C thus receives the successive tea-balls 31 in spaced relation either from a tea-ball machine (not shown) or the finished tea-balls are placed on the belt of the conveyor C in spaced relation by hand or otherwise.

The conveyor C may include an outer end pulley 43 at an extended or receiving end thereof, an inner end pulley 44 at the delivery end, and a suitable leather or fabric belt 45 interconnecting said pulleys. See Figs. 1, 5 and 10. Said belt 45 may have imprinted along the entire length thereof spaced markings 45a to indicate the feeding positions of the tea-balls or other articles delivered by the belt 45 to be wrapped. Said markings 45a serve the purpose of indicating where the articles or tea-balls are to be placed on the conveyor when manually fed, and with tea-balls of the pouch type also to indicate the position of the gathered ends thereof by the tapered marking portions 45b. When the apparatus 40 is used with an automatic tea-ball machine, the belt markings 45a serve to indicate the proper

sequence in the discharge of the tea-balls on the belt 45, and where any displacement or derangement from the correct discharge takes place to readily observe and facilitate rectifying the same.

Said belt 45 moves in the direction of the arrow as shown in Fig. 3 and conveys the tea bags 31 towards a wrapper supply and folding mechanism W as shown in Figs. 1, 3 and 15. The belt 45 as here shown is driven through the outer end pulley 43 which has a sprocket 43a mounted to turn therewith. Said sprocket 43a is driven through a chain 43b and a drive sprocket 43c mounted on a cross power drive shaft 70a located below the conveyor C, the cross power drive shaft 70a being connected with a power shaft through a set of bevelled gears 70b as shown in Figs. 1 and 3. The inner end pulley 44 is also driven from the cross power drive shaft 70a by means of a sprocket 44a mounted to turn with the pulley 44 which is driven through a chain 44b and drive sprocket 44c, said drive sprocket being mounted to turn with the cross power drive shaft 70a as shown in Figs. 2 and 3. The desirability of driving the conveyor C from both ends resides in the fact that it is found that all slippage of the belt 45 or possibly buckling due to jamming is thus eliminated and the markings 45a on the belt will thereby remain in a proper registered arrangement with respect to a wrapper supply and folding mechanism W to which the tea-balls 31 are fed by said conveyor C.

The supply of wrappers may be made from a stack of pre-cut blank sheets in the well understood manner, but as here shown, said supply consists of a continuous strip or web 32a forming a roll 32b which is carried on a reel 51. The latter is rotatably mounted on a stub shaft 52 which is supported on a rigid arm 53 extending up from the frame structure of the apparatus 40 as shown in Figs. 1, 2, 4 and 8. The leading end of the strip 32a from the roll 32b passes between a front feed roller 54 and rear feed roller 55, the front roller 54 being driven from the rear roller 55 through a pair of intermeshed gears 56. As seen from Figs. 2 and 14, said rear roller 55 is journaled in an overhanging bearing 55a and is driven through a sprocket 55b, a suitable chain 55c and a drive sprocket 55d mounted to turn with a cross power drive shaft 70c extending in spaced parallel relation to cross power drive shaft 70a, and like the latter connects with the power shaft 70 through a set of bevelled gears 70d, as shown in Figs. 2 and 3. The front roller 54 is mounted for rotating on a suitable suspended bearing 54a as shown in Fig. 5. The rear roller 55 may be rubber covered and said rollers 54 and 55 may be retained for resiliently clamping the strip 32a therebetween by a suitable tension spring 57, the suspended bearing 54a being suitably pivoted at 54b to permit clamping action by said spring 57.

As seen from Fig. 2, the chain 55c connecting with the cross power drive shaft 70c provides an intermittent rotation of the rear roller 55 through a chain slack take-up 55e. The latter comprises a slideway over which the chain rides, said slideway being carried by an arm or a lever 55f pivoted at 55g. Said arm 55f is resiliently held by a tension spring 55h so that the slideway is forced by constant pressure to take up any slack in the chain 55c. Bearing against the side of the chain 55c between an idler pulley 55j (Fig. 3) and the sprocket 55b is a roller 55k which is mounted for rotation on the upwardly extending end of a rocker lever 55m, said lever being pivoted at 55n. The rocker lever 55m has a lower horizontally ex-

tending end 55p which engages through a suitable linkage 55q with one side of a double cam 80, the latter being mounted to rotate with the drive shaft 70 as shown in Figs. 2 and 3. The chain drive including the chain 55c for the rear roller 55 is so constructed that the take-up above described and the pressure roller 55k co-act when the cam 80 is effective to release or increase the pressure of the roller 55k and thereby loosen or tighten the chain 55c which in turn gives an intermittent rotary movement to the roller 55. The feed of the web 32a by means of the roller 55 is thus also made intermittent in proper timed relation with the operating and wrapping operations hereinafter described, driven from the same power shaft 70. The other side of said cam 80 connects with a shearing or severing means 59 through a suitable linkage 59a so that said cam 80 thus is made to control in proper timed relation both the feeding and cutting of the web 32a. See Figs. 2, 3 and 14.

Referring now to Figs. 5 and 14, the leading end 32a of the strip after being fed downward between the rollers 54 and 55 extends past a member 58 which guides the same between a fixed blade 59b and a movable blade 59c of the shearing or severing means 59. Said strip 32a before being severed is permitted to pass downward beyond the shearing means 59 a distance sufficient in length to make a wrapper 32 through a bowed or arcuate passage 60 along the exterior side of the convex surface of a gate or barrier 61 and an upwardly extending curved fixed guide member 62 mounted above the level of a horizontally extending passage 63 in the path of the movement of the tea-balls 31 at the level of the conveyor belt 45. A downward extending guide 64 above the gate 61 and below the shearing means 59 co-acts with the upper end of member 62 to assure guiding the strip 32a between them before and after being severed to enter and retain its bowed shape within the passage 60. To further guide the end of the strip 32a after intersecting the passage 63 and below the level of the conveyor C, a filler block 65 may be provided which co-acts with a curved guide member 66 for holding the strip 32a in its bowed condition within the passage 60 as is clearly shown in Figs. 5 and 10, said block 65 levels the path adjacent the inner conveyor pulley 44 along which the tea-balls 31 move in the passage 60 beyond the conveyor C.

The curved guide member 66 may be removably supported by being mounted in the upper end 66a of a vertically extending lever bar 66b which has its other end 66c pivoted on the base frame 41, a spring 66d being provided to resiliently press the bar 66b with the member 66 in the direction away from the passage 60 as shown in Fig. 5. The inward movement of the guide member 66 is controlled through a loose linkage 66f by a cam 66e mounted on the power drive shaft. This inward movement is effective at the time when the wrapper 32b is being folded above the tea-ball 31. At other times the spring 66d retains said member 66 to keep the passage 60 open as much as possible.

Before the tea-balls 31 on the conveyor C pass through the gate 61, each is acted upon by a presser plate 67 which serves as a sizing gauge to make certain that the tea-ball, before it is presented to the wrapping operation, does not exceed a thickness to permit a free passage of the tea-ball 31 through the gate 61 when open. In Fig. 10 is shown the position of the plate 67 in effective lowered position with the gate 61 raised,

the tea-ball 31 having just passed beyond the gate 61 and conveyor C. In Fig. 5 the gate 61 is shown in effective position when lowered to bar the passage of tea-balls and the plate 67 raised, a tea-ball 31 being shown in position on the conveyor C just before the plate 67 is lowered into effective gauging position. The gate 61 and presser plate 67 are carried by vertically extending slide rods 61a and 67a, respectively, which are supported by reciprocating movement by a support bracket 68. Movement is given said rods 61a and 67a through suitable levers and linkage 61b and 67b, respectively, which are operated by a double cam 69 mounted to turn with the power shaft 70. The linkage 61b co-acts with one side of the cam 69 and linkage 61b with the other side as shown in Fig. 2.

For moving the tea balls 31 along the conveyor belt 45 with respect to a wrapper 32b after the latter has been severed from the strip 32a, a positive pusher means in the form of separable reciprocatable arms 71 is provided. Said arms 71 are each carried by a double linkage 70g which extends between the belt 45 of the conveyor C. Each of said arms 71 has inwardly extended co-operating fingers 71a which move with the arms 71. When the arms 71 are in spread position they are located rearward with respect to the wrapper supply and folding mechanism W as shown in Fig. 15, the fingers 71a then being separated to permit the free passage of the tea-balls 31 on the conveyor belt 45. Said pusher means move in the direction of travel of the tea balls, and are in effective position for advancing the tea-ball 31 along the passage 63 and pass the gate 61 after it is raised for delivery onto a transfer table T, the wrapper 32b then being folded around the tea-ball 31 during the forward progressive movement of the arms 71 with the fingers 71a as seen from Figs. 3, 10, 13 and 14. Through the linkage 70g the separating and bringing together of the pusher arms 71 with the fingers 70h is controlled by crank arm and rod connections 70j which co-operate with one side of a double cam 93 mounted on the power shaft 70 as shown in Fig. 2. The other side of said cam 93 co-acts through suitable linkage 71f and reciprocates the pusher arms 71 and fingers 71a. Thus the tea-balls 31 as they each successively pass through the wrapper supply and folding mechanism W has a wrapper 32b cut from the leading end of the strip 32a by the shearing means 59 which is folded about the tea-balls 31 as it moves onto the transfer table T as is shown in Fig. 10.

Referring now to Figs. 8, 8a, 9 and 10 the table T is seen to be provided with two sets of U-shaped jaws 72 and 73 which operate on spaced pivots 72a to open and close above and below a recess 74 in the leading end of the transfer table T. The pair of jaws 72 are located to extend along the inner side of the pair of jaws 73 and are adapted to move independent of the latter. Each tea-ball 31 as it moves past the gate 61 has the wrapper 32b folded around it as it enters the recess 74 of the transfer table while both sets of jaws 72 and 73 are in open position as shown in Fig. 10. Said jaws 72 and 73 are thereafter closed when the tea-ball 31 with the folded wrapper 32b is in fully inserted position in said recess 74 and the rim portion thereof is completely clamped from one end of the fold 32c of the wrapper 32b to the other by said jaws so as to temporarily seal the tea-ball 31 within said wrapper. The movement of the inner set of jaws 72

alone is against suitable resilient means such as flat springs 75.

For actuating the movement of the sets of jaws 72 and 73, a prying wedge lever 73b pivoted at 73c is provided. Said lever when moved from a horizontal position shown in Fig. 8 to the tilted position shown in Fig. 10 acts to pry the sets of jaws 72 and 73 open. This tilting operation of lever 73b may be produced through a flexible transmission cable 81 having a screw adjustable terminal 81a which depresses the end of the lever 73b. For positively clamping and retaining the jaws 73 alone a similar flexible transmission cable 82 is provided with a screw adjustable terminal 82a as shown in Figs. 8 and 8a. The other ends of the cables 81 and 82 opposite terminals 81a and 82a, respectively, connect with cam levers 81b and 82b, respectively, which in turn are actuated by cams 83 and 83a mounted on drive shaft 70. See Figs. 2 and 4.

The transfer table T is mounted for turning movement in a horizontal plane on a vertical bearing 76 from the position shown in Figs. 1 and 8 to the position shown in Fig. 3 and has a portion 77 which carries the jaws 72 and 73 for subsequent sliding movement from the position shown in Fig. 3 to that shown in Fig. 8a. This sliding movement is produced through a suitable bell crank 84 and a linkage 84a including a universal joint 84b which allows for the swinging movement of the transfer table T, and is controlled by a double cam 85 mounted on the power shaft 70. Said cam 85 also actuating the turning movement of the table T through a linkage 76a as shown in Figs. 2 and 8. Since the top of the transfer table T both rotates and slides as above described, the flexible transmission cables 81 and 82 for actuating the jaws 72 and 73 are preferably provided instead of more complicated linkages. Thus, besides being turned, the end of the transfer table T with a tea bag wrapped and temporarily sealed is advanced into a seam joint sealer S where the package border 31a with the corrugations 31b is applied and the joint heat sealed.

The transfer table T after it has been turned and entered into the seam joint sealer S, moves from the position shown in Fig. 8 to that shown in Fig. 8a. The sealer then clamps the border portion 31a of the package 30 beyond the outer jaws 73 and heat seals and corrugates the same. As shown in Figs. 9 and 12, the seam joint sealer S has a lower die 78 which may be cushion mounted on a rubber base with a felt top where the wrapper material requires such construction, otherwise said lower die 78 may be made of a suitable metal to correspond in form with the upper die 79. Heat may be supplied by any suitable means such as an electric heater 79a of any well understood construction carried by the upper die 79 and energized from a suitable electric power source (not shown). The upper die 79 is of metal and has the corrugations formed thereon corresponding to those which are applied on the package border 31a shown in Figs. 17 and 19. The dies 78 and 79 are mounted for movement to and from each other on spaced guide rods 90. The actuating movements of said dies are controlled through a toggle linkage 91 which is operatively connected with cam 83 70 mounted to turn with the power shaft 70 as shown in Figs. 2 and 8.

The lower die 78 has the cross-piece portion 78a mounted for sliding movement with respect to the other portions of die 78. The cross-piece 75

78a is retained in effective assembled position by suitable means such as compression springs 78b. The sliding movement of said die piece 78a is provided for the purpose of freeing the path of the package after sealing or separation of the dies 78 and 79. A cam lever 78c is provided for sliding said die portion 78a against the action of spring 78b. Said lever 78c is interconnected with a linkage 96 which in turn is actuated by a double cam 83.

After the sealing operation is completed the sets of jaws 72 and 73 are actuated to open for releasing the sealed package 30 and the transfer table T is returned to its former position aligning with the conveyor C ready to receive the next tea-ball 31 for packaging. The dies 78 and 79 are in the meantime separated with the die portion 78 to permit a pusher plate 95 terminating a crank arm 96 pivoted at 96a to move the finished sealed package 30 from a horizontal position between said dies through a curved chute 97 to a vertical position, in a horizontally extending discharge slideway 98, as shown in Figs. 8 and 8a. This slideway may be made of a width slightly less than the width of the package 30 so that each finished package is retained in vertical position by friction along the sides of the slideway 98 and the successive packages 30 move along the discharge slideway 98 in an upstanding position ready to be removed manually by the operator for counting and placing in containers for shipment. See Fig. 8.

From the above description and the drawings the operation of the apparatus 40 and the packaging method embodying the invention, will be apparent. Tea-balls 31 or other like flat-shaped articles are deposited by a tea-ball making machine, manually or otherwise, on the outer end portion of the conveyor C (Fig. 1) adjacent the pulley 43, each tea-ball 31 being placed in the blank marked spaces 45a of the belt 45, the gathered end of the tea-ball 31 aligning with the tapered marks 45c (Figs. 3 and 15). Since the belt 45 moves continuously, the tea-balls 31 are fed to be successively positioned to lie at a spaced distance apart thereon. The belt 45 as it advances carries the spaced tea-balls 31 and when the leading one reaches the gate 61 it will be stopped if the same is in the lower or effective position shown in Fig. 15. Before the gate 61 is raised to permit the tea-ball 31 to advance through passage 63 (Fig. 6) the presser plate 67 is caused to descend from the elevated position shown in Fig. 5 to its lowered position shown in Fig. 10. This flattens or tamps down the tea-ball 31 should it exceed a thickness that would impede its free passage under the gate 61 when raised (Fig. 10). This gauged thickness of the tea-ball corresponds with the height of the recess 74 of the top of the transfer table T.

As the gate 61 is about to be raised, the arms 71 with the finger 71a are brought from their ineffective position shown in Fig. 15 to the position shown in Fig. 3, and after the gate 61 has fully opened, said arms 71 and fingers 71a close around the rear tapered end and sides of the tea bag 31 and advance the latter through the gate 61 against a cut bowed wrapper 32a in passage 60 and into the recess 74 of the transfer table T causing said wrapper 32b to fold around the tea-ball, the position of said arms and fingers being shown in Figs. 13 and 14.

In the embodiment of the invention here shown, the dimensions of the wrapper 32 is made practically of minimum size so that the least

amount of wrapper material is used and the package made as small as possible. To successfully accomplish the wrapping operation using such limited quantity of material, the tea-ball 31 must be carefully centralized or more accurately aligned with respect to the wrapper than would otherwise be necessary before the folding thereof around the tea-ball to completely insure perfect sealing. This end is accomplished by providing a portion of each of the arms 71 carrying the fingers 71a as a movable section 71b resiliently retained on suitable means such as spaced slide pins 71c and 71d having compression springs 71e and 71f. (Figs. 1, 13, 15 and 16.) The front pair of spring pressed pins 71c are adapted to contact with spaced actuators 71g so that the movable arm sections 71b are forced in closer relation away from other portions of the arms 71 (Figs. 13 and 14) when said arms 71 are at the beginning of their receding position after being fully advanced for moving the tea-ball 30 and the wrapper 32a into the recess 74 (Figs. 9 and 10). The actuators 71g are made so as to be ineffective during the advance movement of the arms 71 permitting the leading spring pressed pins 71c to ride past said actuators, the latter being pivotally mounted against the action of a tension spring 71h for that purpose. In the return movement, however, the actuators 71g engage the pins 71c and depress them for moving the sections 71b closer together against the action of springs 71e and 71f. It should be noted that the length of the arms 71 is such that they extend into the fold 32c of the wrapper 32b and assure that the outer edges of the fold are properly shaped to make the fold of uniform section throughout so that when the arms 71 are withdrawn and the jaws 72 and 73 of the transfer table closed, the clamping action takes place without any distortion of the wrapper material adjacent the free edges. The action of resilient arm section 71b as above described is to give the wrapper 32b at both ends of the fold 32c a short wiping or stroking action to eliminate all possibility of improper forming of the wrapper fold 32b.

Just before the advancing of the tea-ball 31 through the gate 61, the leading portion of the wrapper material 32a cut from the rod 32d is caused to pass along the passage 60 by the intermittent rotation of the rollers 54 and 55, said wrapper portion 32a being fed down to the passage 60 in sufficient amount to form one wrapper. As has been explained above the passage 60 preferably is made bow shaped and as the tea bag 31 is advancing to the gate 61 in the manner described above, the severing means 59 are caused to cut the web 32a and as the tea bag 31 reaches the bowed section of the cut wrapper, said wrapper is folded around the tea bag 31 centralized by the arm 71 with the movable section 71b and the wrapped tea bags then being inserted into the recess 74 of the top of the transfer table T taking the position shown in Figs. 10 and 14. When said insertion of the tea bag 31 and folded wrapper 32a has been completed the jaws 72 and 73 are caused to close on the wrapper portion extending around the tea-ball 31 inwardly from the edge thereof, said jaws temporarily clamping said wrapper portions for completely enclosing the tea-ball 31 in the wrapper 32b. Meanwhile the arms 71 have been retracted to a position shown in Fig. 15 and the next tea-ball 31 on the conveyor C is being advanced towards the gate 61 which has closed after the 70

retraction of the arms 71, the presser plate 67 also being brought back to its ineffective raised position shown in Fig. 5. The transfer table T next is rotated 90° so as to turn the gathered end of the tea-ball 31 with the wrapper toward the heat sealer S, as shown in Fig. 3. The top of the transfer table T is then caused to slide into the heat sealer S so that the free edges of the wrapper beyond the jaws 73 extend between the dies 78 and 79. The latter next are brought together and the heat sealing of the joint extending around the package 30 from one end of the fold 32c to the other takes place. The jaws 72 and 73 are next released and simultaneously the transfer table T is retracted away from the sealer S and is turned back to its original position in alignment with the passage 63 ready to receive the next tea-ball 31 to be wrapped.

The dies 78 and 79 which retain the sealed package are then caused to be separated and the die portion 78a slidably moved out of the path of package to the chute 97. Simultaneously with said movement the pusher plate 95 descends swinging the completed sealed package 30 from the horizontal position shown in Fig. 8a to a vertical stack position in slideway 98 in abutment with the preceding completed package as shown in Fig. 8, the completed packages having passed through the curved chute 97. From this stack position, the packages 30 are readily counted and removed for shipment, the discharge slideway being made of slightly less width than the package 30 so that said packages will always remain in a vertical position.

In the practical operation of apparatus 40, it is found convenient to have a portion of the wrapping operation continue to function while other portions are stopped. There is for such purpose provided, as shown in Figs. 2 and 4, a suitable disconnecting means including hand lever 100 which through suitable linkage 101 extending in the path of movement of a spring pressed pawl 102 of a drive clutch 103 may be set to engage or disengage the pawl 102 for causing all the cams and cross shaft 70c on the drive shaft 70 shown in Fig. 2 to the right of the clutch 103 to be disconnected from the power drive through the portions of the drive shaft 70 to the left of the clutch 103, that is, the portion at the universal coupling 70f and bevel gears 70b which drives the cross shaft 70a. The power source which may be by motor (not shown) connecting with the shaft 70 to the left of the coupling 70e (Fig. 2) or by being connected to operate in timed relation with the discharge means of a tea-ball making machine, will continue to operate the conveyor C while the remainder of apparatus 40 will be controlled through the clutch 103. The latter will be set, as shown in whole lines Fig. 4, when the apparatus 40 is in full operation but when it is necessary to advance the conveyor C because of failure to have a complete consecutive layout of tea-ball 31 on conveyor C then the clutch hand lever 100 is moved to the position shown in dotted lines in Fig. 4 which disengages the spring pressed pawl 102 to make the other portion of apparatus 40 inoperative until the conveyor C has been fully loaded ready for continuous operation. Then, by swinging the lever 100 back to full line position as described above and shown in the drawings all the operations of apparatus 40 are carried through automatically from the time the tea bags 31 are deposited on the conveyor C until they are completely packaged and

delivered in a stack in discharge slideway 98, the timing being predetermined by cam and other mechanisms described. For compactness said cams may be incorporated in apparatus 40 by mounting on the shaft 70 as shown in Fig. 2 and some of the linkage connected therewith may have common pivoting shafts 105 and 106 which are supported on the frame base 41 which extend below said cams and shaft 70 as shown in Figs. 1, 2 and 3.

It is to be understood that the apparatus 40 and the method embodying the invention may be adapted to package more than one tea-ball in a single wrapper and that said method and apparatus may handle with equal facility tea-balls of various shapes, such as square, round or as shown.

It will thus be seen that there is provided an apparatus and method in which the several objects of this invention are achieved and which are well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. The method of packaging a flat-shaped article consisting in feeding articles and a strip from which wrappers are cut in predetermined paths of movement, cutting and bowing a wrapper in a mid-portion thereof after advancing the wrapper into the path of movement of the article, conforming said article to a predetermined size, advancing the sized article into the bowed portion of the wrapper and sufficiently beyond while folding the wrapper around the bottom, front and rear flat sides of the article, clamping the wrapper to completely enclose the article therein inwardly of the free edge portion of said wrapper, and heat sealing the said free portion of the wrapper.

2. The method of packaging flat-shaped articles consisting in feeding the articles in spaced relation and a strip from which wrappers are successively cut in predetermined paths of movement, cutting a wrapper after advancing the strip into the path of movement of each article, conforming said article to a predetermined size, centralizing each sized article with respect to a wrapper and folding the wrapper thereabout, temporarily clamping the wrapper portions inwardly of free edge thereof to enclose the article, and heat sealing the unclamped free edge portions of the wrapper.

3. In a method of sanitary packaging tea-balls, the steps of centralizing successive tea-balls each with respect to a wrapper, compressing the tea-balls greater than a predetermined thickness to form a uniform size, and folding a wrapper about the centralized and sized tea-ball while in the compressed state.

4. A package apparatus of the character described comprising means for conveying articles to be wrapped, means for feeding wrappers in the path of movement of the article, means for conforming the article to a predetermined size, means for folding a wrapper about each sized article, means for clamping the folded wrapper to enclose the sized article therein, and means to

heat seal free edge portions of the wrapper while said clamping means are effective.

5. The apparatus defined in claim 4 in which said folding means include a pusher for advancing successive articles beyond the conveying means and onto the clamping means.

10 6. The apparatus defined in claim 4 which includes a gauging means for compressing each article greater than a predetermined thickness prior to folding the wrapper about the article.

15 7. In a packaging apparatus of the character described, a transfer table top, means for mounting said table top for rotary and sliding movement between an article supply means and a discharge means for the apparatus, means on said table top to receive said article with a wrapper folded thereabout, and means co-operating with said receiving means to clamp said folded wrapper around the article to enclose same, said clamping means temporarily retaining the article within the wrapper and extending inwardly from the free edges of the wrapper.

20 8. The packaging apparatus defined in claim 7 in which means are provided positioned to receive the article clamping retained in the wrapper from said first mentioned receiving means for heat sealing the edge portions of the wrapper.

25 9. In a packaging apparatus of the character described, a transfer table top, means for mounting said table top for rotary and sliding movement between an article supply means and a discharge means for the apparatus, means on said table top to receive said article with a wrapper folded thereabout, means co-operating with said receiving means to clamp said folded wrapper around the article to enclose same including a double set of jaws, and means for concomitantly opening said jaws and for independently closing same.

30 10. The method of sanitary packaging tea-balls of the character described consisting in conforming each tea-ball to a predetermined size, applying a wrapper about each sized tea-ball by first bowing the wrapper and then advancing the sized tea-ball into the bowed portion while folding the wrapper to enclose the sized article, clamping the free edge portions of the wrapper at a distance inwardly of the free edges 45 thereof and adjacent the perimeter of said tea-ball to completely seal the sized tea-ball therein, and heat sealing the unclamped free edge portions of the wrapper while said clamping operation is effective.

50 11. The method of sanitary packaging tea-balls of the character described consisting in conforming a tea-ball to a predetermined size, centralizing the tea-ball with respect to a wrapper, retaining the size of the tea-ball and folding the wrapper thereabout, temporarily clamping the wrapper portions adjacent the tea-ball inwardly from the free edge of the wrapper to completely enclose the tea-ball in the wrapper, and heat sealing the unclamped free edge of 55 the wrapper.

60 12. A packaging apparatus of the character described comprising a conveyer for advanced performed articles to be wrapped, a wrapper supply source, means for feeding wrappers from said source into the path of movement of said articles on said conveyer, means for co-operating with said conveyer, and wrapper feeding means for folding the wrapper about of said articles, a mechanism including a gate and a coacting pusher means for advancing the articles one at 75

a time beyond the delivery end of the conveyer, and means located adjacent the gate to size the articles prior to the folding of the wrappers thereabout by said wrapper folding mechs.

13. The method of sanitary packaging tea-balls of the character described consisting in centralizing the tea-ball with respect to a wrapper and folding the wrapper thereabout, stroking

the wrapper ends during said folding operations, temporarily clamping the wrapper portions adjacent the tea-ball inwardly from the free edge of the wrapper to completely enclose the tea-ball in the wrapper, and heat sealing the unclamped free edge of the wrapper.

MERVIN ALLATT.
